UNITED STATES PATENT OFFICE.

BENJAMIN ABBOTT STEVENS, OF TOLEDO, OHIO.

LATCH.

SPECIFICATION forming part of Letters Patent No. 357,242, dated February 8, 1887.

Application filed November 30, 1886. Serial No. 220,300. (No model.)

To all whom it may concern:

Be it known that I, BENJAMIN ABBOTT STEVENS, of Toledo, in the county of Lucas and State of Ohio, have invented an Improved 5 Latch, of which the following is a specification, reference being had to the accompanying drawings, in which—

Figure 1 is a front view, Fig. 2 a back view, and Fig. 3 a central section, of my improved 10 latch.

The object of my invention is to produce a simple, cheap, and efficient latch for use in all ordinary situations where latches are applicable.

15 Referring to the letters marked upon the drawings in aid of a description in detail of my improved latch, A indicates a plate or escutcheon, which I prefer to cast with three lugs, B B and C, and an aperture, D. The 20 lug C is the pivot-lug, to which the combined latch and handle E is pivoted. The lugs B B form the fastenings of a curvilinear spring-rod, F, provided with central stops, G G, on opposite sides, and with two coiled springs, H H, one on either side of the stops G. The face of the escutcheon may be ornamented or plated, or both, in any desirable way.

I form my latch and handle preferably all in one piece or casting, with two lugs or projections, one, I, passing through the aperture D of the escutcheon, and the other, K, passing through the plate and pivot-lug C, and being fastened by means of a screw or by heading

down, or by means of a cap or collar, L, or in any usual manner. The lug I is provided with 35 two forks, so as to straddle the curved spring-rod and be adapted to receive the pressure of the springs on both sides, which hold the latch ordinarily in the fastening position.

M M indicate rings or collars against which 40 the coiled springs bear; but these are not indispensable.

When desired, I may omit one of the springs and provide a stop for the latch against the force of the remaining spring, as shown at X; 45 but generally it is preferable to employ two springs.

Having described my improved latch, what I claim as new, and desire to secure by Letters Patent of the United States, is—

1. The combination of a latch, latch-handle, and lugs I and K, with a plate or escutcheon provided with an aperture, D, and carrying a spring-rod and one or more springs, substantially as set forth. 50

2. In combination with a pivot-latch, substantially as described, a plate or escutcheon provided with the fastening-lugs B B and pivot-lug C, and carrying one or more springs and spring-rods, substantially as set forth. 55

In testimony whereof I have hereunto subscribed my name.

BENJAMIN ABBOTT STEVENS.
